UNITED STATES PATENT OFFICE

HARRY L. LASHER, OF JERSEY CITY, NEW JERSEY, ASSIGNOR TO MARTIN-COPELAND COMPANY, OF PROVIDENCE, RHODE ISLAND, A TRUSTEESHIP

DESIGN FOR A CENTER BAR FOR OPHTHALMIC MOUNTINGS

Application filed June 4, 1932. Serial No. 43,981. Term of patent 7 years.

To all whom it may concern:

Be it known that I, HARRY L. LASHER, a citizen of the United States and a resident of Jersey City, county of Hudson, and State of New Jersey, have invented a new, original, and ornamental Design for a Center Bar for Ophthalmic Mountings, of which the following is a specification, reference being had to the accompanying drawing, in which Fig. 1 is a front elevational view of a center

bar for ophthalmic mountings showing my new design; Fig. 2 is a plan view; and Fig. 3 is a section taken upon the line 3—3 of Fig. 1, looking in the direction of the arrows.

I claim:

The ornamental design for a center bar for ophthalmic mountings substantially as shown.

HARRY L. LASHER.
